(57) **CLAIM**

The ornamental design for a pedicure spa, as shown and described.

DESCRIPTION

FIG. 1 is a front perspective view of a pedicure spa showing my new design.

FIG. 2 is a left side elevation view thereof;

FIG. 3 is a right side elevation view thereof;

FIG. 4 is a top plan view thereof;

FIG. 5 is a rear elevation view thereof;

FIG. 6 is a front elevation view thereof; and,

FIG. 7 is a front perspective view thereof, with environmental structure shown in broken lines.

The broken line showing of parts of the drawings is included for the purpose of illustrating use and environment and forms no part of the claimed design.
